UNITED STATES PATENT OFFICE.

WILLIAM PRESTON STUNZ, OF LANSDOWNE, MARYLAND, AND LEWIS RICHARD GILBERT, OF KALAMAZOO, MICHIGAN, ASSIGNEES TO THE WEBB TALKING PICTURES COMPANY, A CORPORATION OF DELAWARE

MULTIPLE-RECORD TABLE FOR MOTION-PICTURE MACHINES.

1,418,180.

Specification of Letters Patent. Patented May 30, 1922.

Application filed July 12, 1920. Serial No. 395,595.

To all whom it may concern:

Be it known that WILLIAM PRESTON STUNZ, a citizen of the United States, residing at Lansdowne, in the county of Baltimore, State of Maryland, and LEWIS RICHARD GILBERT, a citizen of the United States, residing at Kalamazoo, in the county of Kalamazoo and State of Michigan, have invented certain new and useful Improvements 10 in Multiple-Record Tables for Motion-Picture Machines; and they do declare the following to be a full, clear, and exact description of the invention, such as will enable others skilled in the art to which it appertains to make and use the same, reference being had to the accompanying drawings, and to the letters and figures of reference marked thereon, which form a part of this specification.

20 Our invention relates to motion picture and sound-reproducing record machines. It has primarily for its object the making of a machine of the type mentioned in which will be embodied a plurality of record-supporting tables, a motion-picture projector to which is fed the picture film containing matter corresponding to that on the record, and a counting mechanism operatively connected with the projector-shaft and having elements corresponding to the number of feet of film to be fed for each record and capable of adjustment to insure the starting of one record table at the proper time in relation to the completion of the record of the other 25 table and the completion or ending of the picture film corresponding to that record so that reproduction of the second record will not begin until the non-recording matter grooves of that record have been passed and 30 the second-producing grooves are reached, thus eliminating the disturbing and disagreeable scratch ordinarily existing in starting a record, and by this elimination producing practically a continuous reproduction without detection of the period of 35 finishing the reproduction of one record and the starting of the other. It has further for its object to provide for better or more exact synchronism between the record and 40 the film, and also to provide for the ready and easy restoration of synchronism between

the record and film in the event of the synchronism being destroyed by the reproducing needle jumping in a groove or from other cause.

55

To the accomplishment of the foregoing and such other objects as may hereinafter appear the invention consists in the elements and their relation one to the other as hereinafter particularly described and then sought to be clearly defined by the claims, reference being had to the accompanying drawings forming a part hereof, and in which—

55 Figs. 1 and 1^a represent a side elevation of the machine with parts in section;

Figs. 2 and 2^a a plan view, with parts in horizontal section;

Fig. 3 a vertical cross-section;

Fig. 4 an end view with parts in section;

Fig. 5 a front view of the counting dials, with one set of dials in section;

Fig. 6 a cross-section through Fig. 5, with the "Begin" dial omitted;

Fig. 7 a side view, looking from the right 75 of Fig. 5, with the "Begin" dial and oscillating plate omitted;

Fig. 8 an end view of the counting dial mechanism looking from the left of Fig. 5;

Fig. 9 a dial, with parts in section, showing the pivoted dog of the ten's dial and cam for actuating the same;

Figs. 10, 11, 12, 13 and 14 views in perspective, with parts in section, showing the counting dials, oscillating plate, and "Begin" 85 dial, of one set of counters, separated from each other;

Fig. 15 a diagrammatic plan view of the counting dials mechanism, showing the relation of the shifting forks for the two 90 record tables;

Fig. 16 a detail view of parts of the counting mechanism, with some of the parts sectioned, looking at the rear of the counting 95 mechanism;

Fig. 17 a detail view of parts of the counting mechanism, with portions omitted, looking at the rear of the counting mechanism;

Fig. 18 a perspective of the counting dials and one of the dogs associated with the 100 parts of Fig. 17, separated therefrom;

Fig. 19 an end view looking from the right

hand side of the counting mechanism, showing one of the "Begin" dials and associated parts;

Fig. 20 a detail plan view of one of the dogs and its latch pawl;

Figs. 21, 22, 23 and 24 detached views of clutching elements of one of the record tables;

Fig. 25 a detail view of the record tables 10 drive shaft and hub on which the clutch elements of Figs. 21-24 are mounted;

Fig. 26 a perspective view of parts of the electric switch throwing mechanism, with the parts separated.

15 In the drawings the numeral 1 designates an electric motor of any approved type which has proper driving connection with shaft 2 that extends through the machine and from which motion is transmitted to

20 various parts of the machine, which shaft has a tachometer 3 connected to one end, and is also provided towards the motor with a suitable governor, for instance comprising a plate 4 having swinging shoes 5 thrown by

25 centrifugal force against periphery of casting 6 under the influence of springs 7 connecting the shoes to elbow levers 8 one end of which bears against a slidable collar 9 movable to bear with more or less pressure

30 against the ends of levers 8 so as to govern the speed of shaft 2, the pressure of collar 9 against levers 8 being controlled by a swinging yoke 10 connected with the slidable collar and depending from shaft 11 and connected by an arm 11^a with a rod 12 connected at its other end with a lever 13 pivoted to a rack-quadrant 14 and which has a

35 slideable latch 15 to engage the teeth of the rack to hold the lever and connecting rod 45 to the adjustment given for the speed desired. For lengthening or shortening the connecting rod 12 in relation to the lever 13 and thus get a more refined adjustment of the rod than by the fixed spacing of the

45 quadrant teeth, the end of the rod is threaded and passed through an internally threaded sleeve 16 having a knurled thumb-nut fast to its outer end, the inner end of the sleeve having a swiveled or rotatable con-

50 nection with the extensions 17 of lever 13 by studs 17^a, engaging a groove in the end of sleeve 16, or otherwise, so that by turning the thumb-nut the rod 12 will be shifted or adjusted longitudinally. Any other suit-

55 able type of governor than that mentioned may be used and the details of governor need not therefore be more particularly shown and described.

The governor controlled motor shaft 2 60 has a worm 18 meshing with a worm wheel 19 fixed to shaft 20 through which shaft motion is transmitted as hereinafter described to the supporting shafts 21 of two record-carrying tables 22 which are operated

65 in alternation as hereinafter described. The

shaft 20 also has fixed to it a toothed wheel 23 which meshes with a toothed wheel 24 mounted to turn freely on the projector shaft and having a bevel gear 25 attached to its face to rotate therewith, which gear 70 meshes with two bevel gears 26 which have free rotation in hubs 27 extending from the hub 28 of a casing or housing 29 mounted freely on the projector shaft, the gears 26 meshing with a bevel gear 30 made fast to 75 the projector shaft 31 so that motion may be transmitted to the projector from the governor controlled motor shaft 2 through the train of gears described at a regulated predetermined normal speed. The planetary gears 24, 25, 26 and 30 constitute also a differential drive for the projector shaft which is controlled by a gear 32 carried by a spindle 33 mounted in the frame of the machine and meshing with a toothed member 80 34 forming a part of the housing 29 so that by turning the gear 32 the housing carrying the gears 26 may be partially rotated in one direction or another relatively to the gear 29 and thus through shifting of the 90 gears 26 speed up or lower the normal speed of the projector according as the gears 26 are shifted in one direction or the other, and thus producing a differential speed. The gear 32 may be turned in one direction or another 95 by a handle or crank 35 pivotally connected to the spindle 33 so that its pivoted end in one position may engage or interlock with a toothed rack 36, attached to the spindle 33 to hold the housing 29 and gears 26 in ad- 100 justed position, and be disengaged from the rack 36 when the housing and gears are to be adjusted for speeding up or retarding the projector shaft for synchronizing the film and record if from jumping of the reproducing needle or other cause they get out of 105 synchronism.

The record tables 22 are brought alternating into action and non-action by clutch mechanism, one for each table, and each of 110 like construction and brought into and out of action as will now be described. The clutch mechanism for each record-table comprises a hub 37 mounted loosely on the record-table power transmitting shaft 20 and upon which 115 hub is mounted a gear wheel 38 (having a limited rotative movement) and meshing with a gear 39 fast on each record-table shaft 21. On the same hub 37, alongside the gear 38, is loosely mounted a disk 38^a having 120 teeth 40 on one face; and, alongside the disk 38^a, there is mounted on the record-table transmitting shaft 20 a shifting clutch-plate 41 and its grooved hub 42 feathered to the shaft 20 so as to be slideable thereon and rotatable therewith, said plate having clutch teeth 43 to engage the teeth on the disk 38^a to clutch one to the other when brought together and also having a cone-shaped ring or cam 44 on the same face to engage a pin 130

53 of a latch-bolt 45 slidably mounted in disk 38^a when brought into engagement therewith, said clutch-plate being shifted to clutching and unclutching position at periodic times by a yoke or fork 46 connected to a sliding bar associated with a counting mechanism and operated as hereinafter described. The hub 37 is held against longitudinal movement on shaft 20 by one end 10 bearing against a bushing in which the shaft is journaled and by a collar 47 at the other end fast to the shaft. In order that the gear 38 may gradually take or pick up the same speed as the record-table transmitting shaft 20 and thus avoid jerking action to the table in taking its motion, a collar 48 is made fast to the hub 37 and has attached to it one end of a spring 49 which is coiled around the hub 37 and attached at its other end to a screw 50 which passes through a curved slot 51 formed in the gear 38 and is threaded in the disk 38^a so that when the clutch-plate 41 is clutched to the disk 38^a motion is transmitted to the gear 38 through the yielding 25 or spring connection, the spring acting as a cushion under its increasing tension and this continues until the screw 50 reaches the end of slot 51 and thereafter the gear 38 and shaft 20 have the same speed during the 30 continued rotation of the record-table. When the screw 50 reaches the end of slot 51 a spring controlled latch 52 carried by gear 38 will engage the end of latch-bolt 45 which is projected by engagement of the 35 cone-shaped ring 44 on clutch-plate 41 against the stud pin 53 projecting from bolt 45 so as to lift the latch-bolt that it may be engaged by the latch 52 and lock the gear 38 and disk 38^a together. When the clutch is 40 released a spring 54 that bears down on latch-bolt stud 53 will lower the latch bolt from engagement with the spring latch 52 and thereupon the recoil of cushion spring 49 will return the clutch disk 38^a to its 45 former position and with the screw 50 to its other limit of movement in the slot 51 of gear 38 for repetition of the action described when the parts are again brought to clutching position. The length of slot 51 50 in gear 38 will be determined by the conditions to be met, and in the illustration given its length is proportioned for one fourth revolution of the shaft 20, or four whole pictures of sixteen pictures per revolution 55 of shaft 20, the loss of the one fourth revolution being discounted when setting the starting point of the reproducing or transmitter needle on the record.

The clutching and unclutching of the respective record-tables to start and stop the same is effected and controlled by a counting mechanism which is set for the number of feet of the picture film to be fed for the respective records and which is controlled in 60 its action through suitable connections with the projector shaft which bears a fixed relation to the moving picture projector so that the counting mechanism measures a predetermined length of film passing through the projector. In the present instance, selected 70 as illustrative, one half foot of film is measured by the unit's dial of the counter but one foot (sixteen pictures) is taken as a standard; a predetermined length of film formed of sections being joined together (a 75 section for each record,) and synchronized, each section for its respective record, and each record being noted with the number of feet of film for that record as a guide for the operator. The counting mechanism comprises sets of dials, one set for each record table, each set being similarly constructed and operating, and therefore a description of one set will answer for both sets. This counting mechanism comprises a casing 80 85 in which is mounted a rock shaft 56 passing through a quill 57, at each end, held fast by a screw 58 to a bushing 59 extending inwardly from the heads of the casing. Made fast by keys to the quill 57 are canis 60 each 90 formed with a depression or notch 61, and mounted loosely on the quill are three dials, a unit dial 62, a ten's dial 63 and a hundred's dial 64, and a setting or "Begin" dial 65, while between the "Begin" dial 65 and 95 the unit's dial is an oscillating drive plate 66 made fast by pins 67 to the rock shaft 56. The ten's and the hundred's dials are each provided on one face with ten teeth 68, and the unit's dial is provided on one face with 100 twenty teeth 69, and the "Begin" dial is formed on one face with teeth 70 and with a rest-plug 70^a between two of its teeth, the teeth and rest plug being formed in the ratio of sixteen teeth to the dial. Each of the 105 dials 62 and 63 has pivoted thereto by a pin or screw 71 a dog 72 one end of which is pressed by a spring 73 into contact with the periphery of cam 60 and the other end of which is disposed to engage one of the teeth 110 on the next adjoining dial so as to move the same one tooth or one tenth of a revolution when and while its other end is in the notch of its cam 60 in the rotation of the two dia's. The oscillating plate 66 is provided on each 115 face with a pivoted dog 74, so disposed as to have one end thereof pressed by a spring 75 so that one dog will engage the teeth 69 of unit's dial 62 and the other dog engage the teeth 70 of the "Begin" dial 65. The "Begin" dial 65 carries a spring-pressed pawl 76 that engages a ratchet 77 keyed to the quill 57 so as to prevent backward movement of the "Begin" dial. The two sets of 120 counting dials are separated one set from the other by a partition 78 through which rock shaft 56 passes; and rocking or oscillatory movement to the oscillating plate 66 is derived through an arm or connecting rod 79 pivoted to the plate and pivotally 125

connected at its other end to a link 80 which at one end is pivotally connected to a rod or arm 81 which is under the influence of a suitable spring (not shown) so as to press the link against a cam 83 made fast to the projector shaft 31 which is so formed with two lobes as shown as to impart two movements to the link 80 in each revolution of the projector shaft and thus oscillate the plate 66 so that the dog on one face thereof will push the units dial the distance of one tooth every time the plate rocks forward so that in every revolution of the projector shaft the units dial will be turned one tenth of a revolution, there being two forward movements of the oscillating plate in every revolution of the projector shaft. The cam 83 is so dimensioned as to give more than $\frac{1}{16}$ of a revolution to rocker-plate 66 but less than $\frac{1}{10}$ of a revolution so that two teeth on unit's dial 62 cannot be pushed at one and the same time.

The counting mechanism also includes two shafts 84, one for each set of dials, made fast in the heads of the counter-housing and 25 the partition 78 (Fig. 16) and on each shaft is loosely mounted three dogs 85, 86, and 87 positioned at the rear of the counter dials, the dog 85 being pressed forward by a spring 88 and dog 87 by a spring 89. The 30 dog 85 has fingers 90 on one face positioned to enter recesses 91 in the peripheries of dials 62, 63 and 64 when the recesses are in alignment, and it has a laterally projecting lug or lip 92 that will lap over the adjoining dog 86, and on its top is provided with a catch-pawl 93 pivoted thereto in position to engage a latch 94 extending from a shifting bar 95 which carries the record-table clutch actuating fork 46, there being a shifting bar 35 and clutch operating fork for each set of counting dials, said catch-pawl 93 holding the clutch fork shifting bar against retraction by spring 95^a until released by the catch-pawl 93 in the outward movement of dog 85 in setting the counting dials. The 40 dog 86 has a pin 96 projecting from its face which when the dog is moved forward by the dog 85 is carried back of a stud 97 depending from the clutch fork 46 so as to permit the bar 95 carrying the fork to be shifted, whereupon the pin will lie back of the stud 97 as shown (Fig. 16) and thus hold the dog 86 in its forward position after the dog 85 has been moved backward in setting 45 the dials. The dog 87 is provided at its upper end with a cam-plate 98 which is held by the spring 89 in the path of a cam 99 on the "Begin" dial 65 and when said cam in the revolution of the "Begin" dial contacts with 50 and presses the dog 87 outward its cam 98 acts on an arm 100 depending from the clutch fork shifting bar 95 so as to shift said bar longitudinally, against the tension of its retracting spring 95^a, for shifting the record-table clutch into unclutching relation

through the clutch-fork. It will be understood that while the several parts described are the same for each set of counting dials, they work in alternation for each set of dials for clutching and unclutching the record tables in alternation, one of the clutch-fork shifting bars being thrown in one direction for its controlled record-table and the other bar in the other direction for its record-table, the parts functioning substantially the same for both tables. Each clutch shifting bar 95 has a pin 101 projecting from one face, both of which pins lie within a fork 102 at the end of an arm 103 which is connected by a pin 104 to a pindle 105 which is revolvable in the end of a stationary bracket-arm 106 and has at its lower end diverging arms or a fork 107 and constituting a rocking switch lever which is thrown in one direction or another from the shifting bars 95 so as to permit a switch to be thrown to bring the transmitter of one record into action and of the other record out of action. This switch lever cooperates with the transmitter switch actuating means as follows: 90 On the projector shaft 31 is loosely mounted a hub 108 having a plate 109 with which is connected an eccentric 110 likewise mounted freely on shaft 31 and also a collar-plate 111 mounted loosely on shaft 31, the eccentric 95 and two plates being connected one to the other by pins 112 so as to turn together, and the eccentric 110 is encircled by a strap 113 from which a connecting rod 114 extends to the arm 115 of a double throw four pole 100 switch 116 which determines the transmitter of the particular record that shall be made active as well as the one that shall be made inactive, it being contemplated to use with the apparatus electric telephone transmitters 105 having the reproducing needles of the records connected therewith of a type well known and in use and not specifically claimed herein and therefore not here described more in detail. The plate 109 is 110 provided with a stop lug 117 which projects into the path of movement of the switch throw lever 107. On the hub 108 is loosely sleeved what for convenience will be designated a friction-clutch plate 118 having on 115 its face next to the plate 109 a pad 119 of suitable material, preferably leather, said friction-clutch plate being connected by a spring 120 with a collar 121 made fast to the projector shaft 31. The rotation of the 120 projector shaft winds up or tensions the coiled spring 120 which tends to turn the friction-clutch plate 118 and which in turn would rotate the eccentric-plate 113 except for the fact that the latter is prevented from 125 rotating by engagement of its stop-lug 117 against the arm of the switch-throw lever 107, and consequently power is stored in the spring 120. When however the switch lever is rocked by movement of one of the shift- 130

ing bars 95 so as to move its arm from engagement with the stop-lug in the eccentric-plate 109, the spring 120 by reason of its stored energy quickly rotates clutch-plate 118 and through its frictional engagement with plate 109 rotates the latter so as to turn the eccentric 110 and through the strap 113 and connecting rod 114 throw the transmitter double-throw four pole switch so as to 10 cut-out one transmitter while the switch is brought into position for bringing the transmitter of the other record into action at the proper time, the eccentric-plate 109 being stopped in a half revolution by the other 15 arm of the switching lever having been moved into the path of the stop-lug 117 so as to arrest the rotation of the eccentric-plate and attached eccentric and hold the two against rotation from frictional contact of 20 clutching-plate 118 until the switching lever is rocked in the other direction by the shifting bar of the set of counters for the other record-table whereupon the eccentric-plate is again released and the stored energy of 25 spring 120 rotates the eccentric to throw the transmitter switch, and so on in repetition.

Operation.

The machine operates as follows: A predetermined length of film synchronized to a multiple of records are joined together. On each record is noted the number of feet of film for that record as a guide to the operator. The film is placed in the projector 30 and one of the records placed on, say the right hand turn-table, it having been noted that the other turn-table was the last used; the dials of the counter for the right hand table are set to the predetermined number of 35 feet noted for the record of that table. The "Begin" dial for this table is set to allow for the number of non-recording grooves of the record on the table, which have been predetermined and noted on the record so that 40 the transmitter reproducing needle of this record will not give forth the reproduction of the record until the point of definite recorded matter is reached at which moment the switch of the transmitter reproducing 45 needle is instantaneously thrown so that the actual reproduction of the record begins the moment the definite recorded matter of the grooves is reached. The reason for this is that usually a number of grooves turned in 50 the beginning of a record have nothing definite recorded and the needle working in these non-productive grooves would give forth scratchy and discordant notes or sounds until the definite recorded matter is 55 reached. This is obviated in the present construction by making provision for the transmitter needle not becoming actively reproductive of sounds until the definite recorded matter of the grooves is reached 60 which is effected by shifting the switch for the reproductive activity of the transmitter at the moment that the definite recorded matter is reached, the switch being thrown at such time through its connections with the counting mechanism, the "Begin" dial 70 of which is set for the switch to be actuated at the end of the non-productive or scratch grooves of the record. With this preliminary statement and with the dials of the counter of the record to be reproduced 75 set for the number of feet of film for that record and the "Begin" dial set for the non-productive grooves in the record, the machine is started. The rocker-plate 66 being 80 oscillated through its connections from cam 83 on the projector shaft 31, the several dials are rotated through their respective dogs or pawls operating as previously described and by the time the definite recorded matter of the record grooves is reached in the rotation of the record table the "Begin" dial 65 has reached the limit of rotation to which it was set for the non-productive matter grooves and then the actuating pawl for the "Begin" dial 85 plays idly upon the rest interval 70^a of its 90 row of teeth so that the rotation of that dial ceases or comes to rest while the other dials continue their rotation, and the cam 99 of the "Begin" dial 65 presses the dog 87 outward so that its cam 98 will bear against the arm 100 of the clutch-fork shifting bar 95 and move said bar sideways so that its pin 101 will contact with the forked end of switch lever 107 and move it from engagement with stop-lug 117 of eccentric-plate 109 and the stored-up energy of spring 120 will shift eccentric 110 and through the connecting rod 114 throw the pole switch 115 so as to close an electric-circuit (not shown) 100 through the transmitter for the record and thus give audible reproduction from the record grooves. At the same time that the shifting bar 95 is moved by the cam 98 the clutch-fork of that bar is moved with the bar so as to unclutch the other or left 110 hand turn table, (looking at Fig. 16, which is a view from the rear of the machine), and said bar is held against spring retraction into clutching position, when the cam 99 releases pressure on dog 87, by the latch 115 93 engaging the catch 94 depending from the shifting bar carrying the clutch-fork of the table unclutched. By this time also, the units, tens and hundred's dials of the unclutched table have reached the limit of the 120 points of rotation for which they were set and the recesses 91 in their peripheries are in register and the dog 85 has been thrown inward so that its fingers 90 have entered said recesses, and in this movement of the 125 dog it has pressed the dog 86 inward so that its upper end bears against the tails of the pawls 74 of its oscillating plate so as to hold said pawls from engaging with the teeth of the "Begin" and unit dials of the 130

set of counters for that (now non-rotating) table and making said dials for the time inactive. In the inward movement of the dog 86 its pin 96 has been moved back of the 5 plane of movement of the stud 97 of the clutch-fork for that table so that even when the dog 85 moves outward in setting the dials of that table the dog 86 will be held in its inward position against the tails of the 10 rocking-plate pawls by the stud 97 bearing against the front face of pin 96, which is during the time the counting dials are being set. While one turn-table and its associated parts are operating, the counting 15 dials of the other table, say the left hand table, are set for the number of feet of film for that record and for the scratch grooves of the record. When the dials of the record-table which is operating have 20 reached the limit for which they have been set the recesses 91 in their peripheries are in register whereupon the fingers of the dog 85 enter the recesses and its companion dog 86 is pressed inward against the tails of its 25 oscillating plate pawls and the latch 93 disengaged from the catch 94 so that the shifting bar 95 carrying the clutch fork of the other, or left hand table, can be retracted by its spring 95^a into clutching position for 30 that or left hand table so as to start that record-table and whose transmitter needle will travel the unrecorded matter grooves of that record. By the time that the end of the unrecorded or scratch grooves of this 35 record has been reached, the cam 99 on the "Begin" dial of this set of counters has reached the point of contact with dog 87 of that set and said dog being pressed outward its cam 98 bears with side pressure 40 against the arm 100 depending from the shifting bar of the other or right hand table and moves said bar against the tension of its spring 95^a so as to move the fork of the right hand table and unclutch that table 45 and at the same time cause pin 101 to shift the electric pole switch of the transmitter circuit and so that the recorded matter of the record may be given forth by the transmitter. At the time that the shifting clutch 50 bar of the right hand table is moved towards the left hand table the latch 93 of the dog 85 of the left hand table counters engages the depending arm 94 of that bar and holds it against spring retraction until 55 released, and at the same time the lug 97 of the other shifting yoke passes over and stands in front of the pin 96 of dog 86 of the right hand record-table so that the dog will hold the oscillating-plate pawls of that 60 set out of operative connection with the dials of that table while being set for the next record to be placed on the table. It will be noted from the foregoing that one table is running while the other table is running for 65 the length of its unrecorded matter grooves and that when the matter recorded grooves of the latter is reached and reproduced by its transmitter the other table stops in its rotation. That fact together with the quick throw of the transmitter switch by the stored 70 up energy of spring 120 makes it possible to have the ending of a portion of a sentence on one record and the beginning of the remainder on the other record practically non-detectable because of the quick shifting or 75 change from one record to the other. It will be understood that the tables operate in alternation and that the record is placed on one and its counting dials set while the other is operating, and that the parts of one 80 are substantially the same in formation, arrangement and operation as the other. It will also be noted that the counting mechanism is operated directly from the shaft which drives the moving picture projector 85 and so counts the number of film feet that if a mistake is made in setting the needle of transmitter in the correct place or groove of the record the error can be corrected by adjustment through the differential synchronizing gears 26, 29, 32, 34. 90

The upper end of each record turn-table shaft 21 is formed with a reduced cone-shaped end 122 and threaded stem 123 to which is fitted a split-nut 124 having a 95 knurled thumb-piece 124 so that by screwing down the nut it will be expanded to grip the wall of the record on the table and prevent the record from slipping on the table which if occurring would put the record out 100 of synchronism with the film.

A plate attached to a suitable part of the counting mechanism has spring fingers 126 which bear against the peripheries of the units, tens and hundred's dials, in the depressions where the numerals of the dials are stamped, so as to prevent slipping of the dials on the quill in which they are mounted. 105

The numeral 127 indicates a box containing electrical equipment for the double pole 110 throw switch to throw the current from one transmitter to the other and also the main current switch for the entire machine; 128 the starter hand shaft for the electric motor; 129 a resistance lamp for the transmitters; 115 130 the sockets for the terminals of the direct circuit and voice circuit of the respective transmitters; and 131 a test receiver horn; the electric circuits not being shown because they are within the expert knowledge 120 of the skilled in the art, and not claimed herein.

The counting mechanism described acts as a subtractor instead of as an addition counter, and while the construction described 125 for it is preferred for use yet where other forms of counting devices already on the market suitable for the purposes may be used such substitution can be made without departing from other features of the invention. 130

We have described with particularity the preferred details of various parts and their relative arrangement but it is to be understood that changes can be made in various details and essential features of the invention retained.

Having described our invention and set forth its merits what we claim is:

1. A plurality of record supporting tables, a counting mechanism for each record table having successively acting dials adapted to be set for the number of revolutions of each record employed, and means for rotating one record table and its companion counting dials in unison and stopping the rotation of the other table while its companion counting dials are being adjusted for the record of that table. 70
2. A plurality of record supporting tables, a counting mechanism for each record table having successively acting dials adapted to be set for the number of revolutions of the record employed, means for rotating one record table and its companion counting dials in unison, and means for stopping the rotation of one table after a predetermined period of rotation of the other table. 75
3. A plurality of record supporting tables, a counting mechanism for each record table having successively acting dials adapted to be set for the number of revolutions of each record employed, means for rotating one record table and its companion counting dials in unison and stopping the rotation of the other table while its companion counting dials are being adjusted for the record of that table, a motion-picture-film projector shaft, and means cooperatively associated with the projector shaft and counting mechanism for actuating the latter from the projector shaft. 80
4. A plurality of record supporting tables, a counting mechanism for each record table having successively acting dials adapted to be set for the number of revolutions of each record employed, means for rotating one record table and its companion counting dials in unison, means for stopping the rotation of one table after a predetermined period of rotation of the other table, and means for making audibly effective the reproductive transmitter needle of the record that has made a predetermined number of revolutions. 85
5. A record supporting table, a power transmission shaft and a clutch mechanism for operatively connecting the transmission shaft and record table, said mechanism comprising a transmission gear connected with the shaft of the record table, and loosely mounted on the power transmission shaft, a clutch-plate mounted loosely on the hub of the transmission gear, a spring connected with the hub of said gear and with said clutch-plate, and a clutch member rotatable with the power transmission shaft and adapted to be brought into locking relation with the clutch-plate to place the spring under tension and transmit motion to the transmission gear, said gear and clutch-plate 90 having a positive interlocking engagement with each other at a point in their rotation whereby the speed of rotation of the table is brought up gradually to the speed of the power transmission shaft. 95
6. A plurality of record supporting tables, means for rotating one table and stopping rotation of the other in alternation, a picture film projector shaft, a clutch mechanism associated with said shaft and comprising two plates loosely mounted on the shaft and one having a slidable connection with the other, one of the plates being connected by a spring to the shaft to transmit motion through the spring to the plate, the other plate being connected with an eccentric, a switch lever positioned to have a part to lie within the path of a part of the eccentric to lock the eccentric-plate against rotation, and means for releasing the lever from engagement with the eccentric-plate to permit the eccentric-plate to be rotated from the stored up energy of the spring when one of the record-tables is to be stopped in its rotation. 100
7. A motion picture and sound reproducing machine comprising a plurality of record supporting tables and a film projector shaft, a counting mechanism for each record table having successively acting dials adapted to be set for the number of revolutions of each record, one of said dials being rendered inactive when the end of the unrecorded matter is reached and the other dials continuing active throughout the recorded matter of the record, and means for rotating one record table and its companion active computing dials and automatically stopping rotation of the other table at the end of the unrecorded matter and beginning of the recorded matter of the companion table for adjustment of the counting dials of the non-rotating table. 105
8. In a motion picture and sound reproducing machine comprising a plurality of record supporting tables and a film projector shaft, of a counting mechanism for each record table having successively acting dials adapted to be set for the number of revolutions of each record, means connecting the counting mechanism with the projector shaft for actuating the counting mechanism from said shaft, and means actuated from the counting mechanism for automatically stopping the rotation of one record table upon cessation of activity of its associated setting dials and automatically starting rotation of the other table upon activity of its associated setting dials. 110
9. A motion picture and sound reproducing machine comprising a plurality of record supporting tables and a film projector shaft, of a counting mechanism for each record table having successively acting dials adapted to be set for the number of revolutions of each record, means connecting the counting mechanism with the projector shaft for actuating the counting mechanism from said shaft, and means actuated from the counting mechanism for automatically stopping the rotation of one record table upon cessation of activity of its associated setting dials and automatically starting rotation of the other table upon activity of its associated setting dials. 115

ing machine comprising a plurality of record supporting tables, a film projector shaft, and an electrical sound transmitter for each record, a counting mechanism for each record table having successively acting dials adapted to be set for the number of revolutions of each record, means connecting the projector shaft with the counting mechanism for actuating the counting mechanism from 5 said shaft, means actuated from the counting mechanism for automatically stopping the rotation of one table during inactivity of its associated setting dials and starting rotation of the other upon activity of its 10 associated setting dials, and means connecting the counting mechanism with the switch of the electrical sound transmitters and operating to throw the electrical transmission current into one transmitter at the end of 15 the non-recorded matter and beginning of the recorded matter of its record table and simultaneously cut-off the transmission cur- 20

rent from the other transmitter at the termination of the recorded matter of its record table, as predetermined by the setting dials 25 of the counting mechanism for the respective records.

In testimony whereof we have hereunto set our hands.
